UNITED STATES PATENT OFFICE.

CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

AUXILIARY SWITCH.

Application filed February 26, 1925. Serial No. 11,887.

This invention relates to electrically-operated electric circuit interrupters and switches.

An electrically-operated circuit interrupter is usually provided with two separate electro-magnets, or solenoids, which are arranged to effect the closing and opening of the circuit interrupter. The circuit interrupter may be remotely controlled through a suitable control circuit including a remotely-disposed and manually-operable circuit-controller for each electro-magnet; and the manual operation of a circuit-controller is arranged to effect either the closing or the opening of the interrupter, dependent upon the particular circuit-controller operated.

An object of this invention is the provision of an auxiliary switch associated with the circuit interrupter and operated therewith, and by the mechanism thereof, in such a manner that the control circuit for the opening and closing electro-magnets is controlled and interrupted by the auxiliary switch, whereby to eliminate relays heretofore considered essential to the control circuit.

A further object is generally to improve electric switches and interrupters and control circuits therefor.

Fig. 1 is a fragmentary side elevation of a circuit interrupter provided with electrically operated opening and closing mechanism adapted for remote control and an auxiliary switch embodying the invention associated with said circuit interrupter and electrically operated mechanism.

Fig. 2 is a side elevation of the auxiliary switch and illustrating the switch in a position in which the closing electro-magnet circuit is closed.

Fig. 3 is a front elevation of Fig. 2.

Fig. 4 is a view similar to Fig. 2 but with some parts shown in section and with the switch in a position in which the opening electro-magnet circuit is closed.

Fig. 5 is a perspective detail illustrating more particularly the construction and disposition of the opening circuit contact members.

Fig. 6 is a perspective detail of the supporting bracket for a contact member of the closing circuit.

Fig. 7 is a perspective detail of the carrier for a contact member of the closing circuit.

Fig. 8 is a vertical section through the movable member of the auxiliary switch.

Fig. 9 is a diagram of the control circuit with which the auxiliary switch may be associated.

Fig. 10 is a section along line 10—10 of Fig. 4.

The circuit interrupter 10 is provided with electrically-operated mechanism by which it may be opened and closed; and the electrically-operated mechanism includes a housing 12 which contains a solenoid 14 adapted to be energized to effect the closing of the interrupter. The mechanism also includes a housing 16 which contains a solenoid 18 adapted to be energized to open, or trip, the interrupter. Said mechanism includes an operating shaft 20 which is adapted to be moved angularly in a clockwise direction to effect the closing of the interrupter, and said shaft is adapted to be so actuated by said closing solenoid, which solenoid is operatively connected with said shaft through suitable operating members including the plunger 22 which is reciprocable within said solenoid. Said shaft is adapted to be locked in the closed position of the interrupter by means including the latch 24, which latch is carried loosely by an arm 26 fixed to said shaft. Said latch is adapted to engage releasably with a stationary-supported latch-roller 28; and a plunger 30 operable within said opening solenoid 18 is adapted to trip the latch, when said solenoid is energized, and permit the circuit interrupter to move to open position and the shaft 20, consequently, to rotate in a counter clockwise direction.

The auxiliary switch embodying the invention and adapted to control the circuits for the closing and opening solenoids is carried and actuated by the electrically-operated mechanism for the circuit interrupter. Said switch includes a more or less U-shaped metal frame having the upstanding and approximately parallel spaced side walls 32 and the integral bottom connecting wall 34, which bottom wall rests upon the housing 12 and is secured thereto by suitable means as the bolts 36. Said frame is open at the back and said back-opening is closed by the heat-resisting plate 38, which plate is also an electrical insulator and forms the back-plate or wall of an arc-chamber. A heat-resisting plate 40 is disposed against the upper portion of the inner face of each upstanding side wall 32 and a similar plate 42 is disposed mid-

way between said plates 40 whereby to form two isolated arc chambers or chutes 44 and 46 which are open at the front and at the top and bottom. Said plate 42 may be maintained in position by the heat-resisting spacer-blocks 48 and bolts 50, which bolts pass through the opposite side walls 32 of the frame.

The circuit through the closing solenoid is adapted to be interrupted and the interrupting arc drawn in the arc chambers; and a stationary and similar switch member is disposed in each arc chamber. Each stationary switch member includes a supporting bracket having the spaced and approximately parallel side walls 52, the rear wall 54 which is at approximate right angles to the side walls, and the downwardly inclined bottom wall 56. Said bracket is attached to the insulating rear wall 33 by a bolt 58, which bolt also forms a terminal connector for the stationary switch member. The contact member 60 is provided with an upstanding contact portion 62 which is adapted to be engaged by the cooperating movable contact member. Said contact member 60 is carried yieldingly by said bracket and, for this purpose, is attached removably, by suitable means as screws 64, to the upper wall 36 of a contact support. Said contact support is formed or provided with two depending arms 68 which are disposed between the side walls 52 of the supporting bracket and are pivoted to the forward portions thereof by the pivot pin 70. A rod 72 is passed loosely through an aperture in the upper wall 66 of said contact support and also loosely through an aperture 74 in the bottom wall 56 of said supporting bracket and is retained in such relation by the enlarged head 73 at the upper end and the washer 75 and pin 76 at the lower end of said rod. A compression spring 78 encircles said rod between said contact support and bearing support and is arranged to support the contact support yieldingly in raised position, as in Fig. 4. When the contact member is engaged, however, said spring is adapted to yield and permit the contact member to move rearwardly to some position as illustrated in Fig. 2. The arrangement is such that, when the auxiliary switch is operated to open the closing coil circuit, the stationary contact member can follow the movable contact member for a sufficient distance in its opening movement to ensure the latching of the switch in closed position before the closing coil circuit is interrupted.

The contact member is positively connected electrically to the terminal connector, or bolt 58 by a flexible conductor 80.

The stationary switch members in the two arc chambers are adapted to be connected electrically, or bridged, by the movable switch member.

The movable switch member includes an

arm 82 which is carried by the cover-plate 84 of the coil housing 12. Said arm is formed with a rearward extension 83 at its lower end which is received in a recess in a lug 86 of said cover plate and is pivoted to said lug 70 by a pin 88.

Said arm 82 is extended upwardly above its pivotal support and two bars 89 and 90 are secured to opposite sides of the upper portion of said arm. Said bars are insulated from said arm by the interposed insulating blocks 92 and are attached together and to said arm by bolts 94, which bolts serve to connect said bars electrically. Said bolts are insulated from said arm by the insulating 89 enclosing bushings 96. The spacing of said bars is such that each bar is adapted to enter and reciprocate within an arc chamber.

The upper ends of said bars are reflexed laterally to form seats 98, to which seats the movable contact members 100 are secured removably by screws 102. Said contact members may be similar to the stationary contact members 60.

When said bars are moved sufficiently into the arc chamber said contact members are adapted to engage with the stationary contact members 62 and thereby bridge them, the bridging circuit including the bolts 94.

The contact members for the opening coil are carried by the insulating side plates 40 and at the forward portions thereof. Said contact members include the reflexed spring fingers 104 which are attached to said plates by bolts 106 and extend into the arc chambers 109 in positions to be engaged and bridged by the bars 89 and 90 in one position thereof. Said bars may be provided with replaceable contact plates 108 which are adapted directly to engage said spring fingers. 105

When the switch is in the position illustrated in Fig. 4, it is in position to control the circuit through the opening coil and when in the position illustrated in Fig. 1 it is in position to control the circuit through the 116 closing coil.

The operating mechanism for the auxiliary switch is arranged to have a lost motion connection with the circuit interrupter mechanism whereby the switch will be actuated to 115 open the control circuit for the opening and closing coils only after the interrupter has been moved sufficiently to ensure its complete operation on either opening or closing, as the case may be. 120

The operating mechanism includes a pair of links 110 which are disposed on opposite sides of said switch arm 82 and are pivoted to a forward extension 83 thereof by the pivot pin 112. Said links are disposed on 125 opposite sides of an arm 114 and are pivotally connected therewith by the pin 116, whereby to form a toggle which is arranged to provide a quick interruption of the closing coil circuit. Said arm 114 is pivoted to an out- 130

standing lug 117 of the cover plate 84 by the pivot pin 118. A retractile spring 120 is connected between the pivot pins 118 and 112 in a position to move across the toggle-joint and serves to break said toggle rapidly when said arm 114 is moved to interrupt the closing coil circuit. Said arm 114 is extended upwardly above the toggle-joint pivot 116 and is provided with an extension 122 which is adapted to engage a projection, as a pin 124 of the links 112, whereby to limit the over-shot movement of the toggle in one direction. The upper ends of said links, above the pivot pin 112, are formed with the projections 125, which projections are adapted to engage with a pin 126 carried by the switch arm 82, whereby to limit relative angular movement between said links and arms in one direction.

Said arm 114 is extended downwardly below its supporting pivot 118 and its lower end is reflexed laterally to form a seat 128 to the lower face of which a cam block 130 is attached by bolts 132. Said cam block is formed or provided with angularly-related cam faces 134 and 136, of which the face 134 is adapted to be engaged to open the closing coil circuit and the face 136 to open the opening coil circuit.

The operating means for said arm 114 includes a hub 138 which is fixed to the operating shaft 20 below said cam block. Said hub is formed or provided with two outwardly divergent arms 140 and 142 between which said cam block is disposed. Roller-blocks 144 and 146 are carried by said arms and bear rollers 148 and 150 which are adapted to engage with said cam faces 134 and 136 respectively. Said roller blocks are adjustable inwardly toward each other by varying the thickness of the shims 152 in the arm-recesses of said blocks and said blocks are fixed to said arms by bolts 154 which are screw-threaded into said arms.

In the position of the parts illustrated in Fig. 4 the circuit interrupter is closed and the control circuit for the opening coil of the interrupter is closed through the auxiliary switch. When the opening coil is energized the mechanism is actuated to open the interrupter and the operating shaft 20 is turned in a counter-clockwise direction, and toward the left. This movement forces the roller-block 146 against the face 136 of the cam block 130 and moves the toggle members, comprising the arm 114 and links 112, and switch arm 82, while the parts maintain about the relative positions shown in Fig. 4, toward the closing coil contact members, ultimately interrupting the opening coil circuit at the contacts 104. The length of engagement between these contacts and the bars of the movable switch member is adapted to be sufficient to permit the circuit interrupter to be definitely moved toward open circuit position before the opening coil circuit is posi-

tively interrupted. During the latter part of the movement of the circuit interrupter in an opening direction, the movable contact members of the auxiliary switch are brought into engagement with the cooperating stationary contact members for the closing coil circuit, whereby to close the circuit. Due to the yielding support of said stationary contact members, the switch arm continues to move in the same direction, while maintaining contact, until the switch arm is brought up against the forward end of the supporting bracket for the stationary contact members as illustrated in Fig. 2. Further movement of the operating shaft in the same direction now serves to straighten the toggle connected with the switch arm, and move the toggle member into an overshot position as illustrated in Fig. 2.

In the full open position of the circuit interrupter the left-hand roller 148 is disposed a substantial distance away from the lower end of the operating arm 114.

When the closing coil is energized and the circuit interrupter moves toward closed position, the operating shaft 20 is rotated in a clockwise direction, Fig. 2, and moves said roller 148 toward the lower end of said operating arm 114. The mechanism is so constructed and arranged, however, that actual engagement is not made until the circuit interrupter is about in full closed position and in position to be locked closed by the latch 24. Further movement of said roller 148 in the same direction serves to break the toggle of the auxiliary switch and the spring 120 serves to move the switch arm rapidly toward the left independently of movement of the operating shaft 20, and thereby rapidly to interrupt the closing coil circuit; the latch 24 having first operated to lock the interrupter in closed position. The movement of the switch arm to open the closing coil circuit is such that it closes the opening coil circuit, as illustrated in Fig. 4.

Fig. 9 illustrates a control circuit for the closing and opening coils. The remote circuit-controller may have two manually-operable circuit-closers normally held in open circuit position and adapted to be held closed manually to close the control circuit. The circuit closer 200 may govern the circuit for the opening coil 18 and the circuit closer 202 may govern the circuit for the closing coil 14.

The bridging member of the auxiliary switch, designated by the numeral 204 in this figure, is adapted to control the closing coil circuit when the circuit interrupter is open as is indicated in the full lines, and control the opening coil circuit when the interrupter is closed, as is indicated by the dotted lines. The structure may be otherwise modified without departing from the spirit of the invention.

I claim:

1. An electric switch having the combination of a pivoted switch arm, operating mechanism therefor including a toggle connected with said arm, means including a spring arranged to hold said toggle releasably in overshot position, an operating member for said operating mechanism arranged to move said toggle positively both into and out of overshot position, and means providing a movement of said switch arm independently of said operating member including a lost-motion connection between said operating member and one of the members of said toggle. 70
2. An electric switch having the combination of a pivoted switch arm, operating mechanism therefor including a toggle eccentrically pivoted to said switch arm, means including a spring arranged releasably to hold said toggle in set position, and an operating member arranged to operate said toggle positively into and out of set position, said operating member having a lost motion connection with said toggle. 80
3. An electric switch having the combination of a support, a switch arm pivoted to said support, a toggle comprising an operating arm pivoted to said support and a link pivoted to said operating arm and also to said switch arm, means to limit the relative angular movement of said link and switch arm in one direction, means to limit the movement of said toggle members in an overshot condition thereof, a tensile spring extended across the pivotal connection of said link and operating arm and arranged to hold said toggle yieldingly in overshot position, and a reciprocable operating member disposed beneath said operating arm and having lost motion connection therewith arranged to operate said toggle positively into and out of over-shot position. 90
4. An electric switch having the combination of a support, a switch arm having an enlarged base one side of which is pivoted to said support, a link comprising a toggle member pivoted to the other side of said base, an operating arm disposed beneath said switch arm and pivoted intermediate its ends to said support and having pivotal connection with said link, whereby to form a toggle therewith, projections carried by said link and operating arm arranged to cooperate to hold the toggle in an overshot condition, cooperating projections carried by said link and switch arm arranged to limit relative movement therebetween in one direction, a tensile spring connected with said switch arm and arranged to be moved across the toggle-joint, and a reciprocable operating member disposed beneath the free lower end of said operating arm and having lost motion connection therewith. 100
5. An electric switch having the combination of a pivoted switch arm, operating means for said switch arm including toggle members and a tensile spring connecting said toggle members, one of said toggle members including an operating arm having a pivotal support therefor intermediate its ends, opposed cam surfaces carried by a free end of said operating arm, and an operating member having lost motion connection with said operating arm arranged to engage said cam surfaces. 110
6. An electric switch having the combination of a pivoted switch arm, operating means for said switch arm including toggle members and a tensile spring connecting said toggle members, one of said toggle members including an operating arm having a pivotal support therefor intermediate its ends, an operating member having lost motion connection with said operating arm including an angularly reciprocable shaft disposed beneath a free end of said operating arm, and a hub carried by said shaft having two divergent arms disposed on opposite sides of and spaced from and free from positive connection with the end of said arm. 120
7. An electric switch having the combination of a pivoted switch arm, operating means for said switch arm including toggle members and a tensile spring connecting said toggle members, one of said toggle members including an operating arm having a pivotal support therefor intermediate its ends, a cam block carried by the free lower end of said operating arm, and an operating device including an angularly-reciprocable shaft disposed beneath said operating arm, a hub fixed to said shaft having two upwardly divergent arms which are disposed on opposite sides of said cam block, and cam rollers carried by said arms and arranged to engage said cam block. 130
8. An electric switch having the combination of a pivoted switch arm, operating means for said switch arm including toggle members and a tensile spring connecting said toggle members, one of said toggle members including an operating arm having a pivotal support therefor intermediate its ends, a cam block carried by the free lower end of said operating arm, and an operating device including an angularly-reciprocable shaft disposed beneath said operating arm, a hub fixed to said shaft having two upwardly divergent arms which are disposed on opposite sides of said cam block, cam rollers carried by said arms and arranged to engage said cam block, and means to adjust said cam rollers on said arms in a direction toward and away from said cam block. 140
9. An electric switch having a pivoted switch arm, operating means therefor including a toggle arranged to be set to hold said switch arm releasably in one position, means including a spring associated with said toggle and arranged to oppose the setting thereof, 150

- means including an abutment arranged to limit the movement of said switch arm, said means also arranged to restrict the opposing action of said spring, and actuating means having a lost motion connection with said toggle arranged to break said toggle to release said switch arm.
10. An electric switch having a movable switch member including a movable switch arm, a stationary switch member including a contact member, means to support said contact member yieldingly in position to be engaged by said switch arm and yield in such engagement, means to limit the engaging movement of said switch arm, operating means for said switch arm cooperating with said limit means to hold said switch arm releasably in engagement with said contact member, and actuating means having a lost motion connection with said operating means arranged to move said switch arm in both directions.
11. An electric switch having a stationary switch member including a bracket having a forward projection, a contact member pivotally carried by said bracket above and to the rear of said projection, means yieldingly supporting said contact member in such relation, and a movable switch member including a pivoted switch arm arranged to engage said contact member and thereafter engage the projection of said bracket.
12. An electric switch comprising a pair of spaced insulated stationary switch members, and a cooperating movable switch member including a pivoted switch arm, a pair of bars carried by and disposed on opposite sides of and insulated from said switch arm and arranged to cooperate with said stationary switch members, and means electrically connecting said bars.
13. An electric switch comprising a pair of spaced insulated stationary switch members, and a cooperating movable switch member including a pivoted switch arm, a pair of bars carried by and disposed on opposite sides of and extended a substantial distance above and insulated from said switch arm and arranged to cooperate with said stationary switch members, and means electrically connecting said bars also mechanically securing them to said switch arm.
14. An electric switch comprising a pair of spaced insulated stationary switch members, and a cooperating movable switch member including a pivoted switch arm, a pair of bars carried by and disposed on opposite sides of and extended a substantial distance above and insulated from said switch arm and arranged to cooperate with said stationary switch members, insulating blocks interposed between said bars and said switch arm, and bolts passed through said bars and switch arm and electrically insulated from said switch arm arranged electrically to connect 65 said bars.
15. An electric switch comprising a pair of spaced and insulated stationary switch members, and a cooperating movable switch member including a pivoted switch arm, a pair 70 of conducting bars disposed on opposite sides of and extended a substantial distance above and insulated from said switch arm, and means attaching said bars to said switch arm also electrically connecting said bars, said 75 bars having laterally-extended end-portions and contact members carried by said end portions.
16. An electric switch comprising an insulating casing providing two separate arc 80 chambers disposed side by side and open at the front, an insulated switch member disposed in each chamber, and a movable switch member including a pivoted arm disposed in front of said chamber and a bridging member carried by and insulated from said arm, said bridging member overlying both arc chambers and having extensions arranged to be moved into said arc chambers and engage and electrically connect said stationary switch 85 members.
17. An electric switch including an insulating casing providing two separate arc chambers open at the front, an insulating barrier separating said chambers, a stationary switch member disposed in the rear of each chamber, and a movable switch member including a current conducting bridging member disposed on opposite sides of said barrier and arranged to engage and electrically connect 90 95 said stationary switch members.
18. An electric switch including an insulating casing providing two separate arc chambers open at the front, an insulating barrier separating said chambers, a set of stationary switch members disposed in the rear of said chambers, a second set of stationary switch members disposed in the front of said chambers, and a movable switch member including 100 105 a bridging member disposed on opposite sides of said barrier and movable alternately into engagement with both sets of stationary switch members.
19. An electric switch including an insulating casing providing two separate arc chambers open at the front, one set of stationary switch members disposed at the rear of said chambers, a second set of stationary switch members disposed at the front of said chambers, and a movable switch member including 110 115 a pivoted switch arm, a bridging member carried by and insulated from said switch arm, said bridging member including two bars movable within said arc chambers and arranged to make lateral engagement with said second set of stationary switch members, said bars having laterally-extended end-portions, and contact members carried by said end-portions.

tions arranged to engage said first set of stationary switch members.

20. An electric switch including an insulating casing providing two separate arc chambers open at the front, a stationary switch member disposed in the rear of each chamber, a movable switch member including a pivoted arm having a contact member for each stationary switch member, said contact members disposed to operate within said arc chambers, a toggle connected with said switch arm, a tensile spring connected with said toggle and arranged to be moved on opposite sides of the toggle joint whereby to actuate the switch arm rapidly, and an operating member for the switch having a lost-motion connection with one of the toggle members.

21. An electric switch comprising the combination of a pair of spaced stationary contact members, a pivoted switch arm movable from one to the other of said contact members, actuating mechanism for said switch arm including a thrust toggle having an operative connection with said arm, an operat-

ing member having a lost motion connection 25 with said toggle arranged to affect the movement of said switch arm alternately from one to the other of said stationary contact members, and a spring operable on the collapse of said toggle to move said switch arm rapidly 30 from one to the other of said contact members independently of a corresponding movement of said operating member.

22. An electric switch comprising a pair of spaced insulated stationary switch members, 35 an insulating barrier disposed therebetween, and a cooperating movable switch member including a pivoted switch arm disposed beneath and in alignment with said barrier, a pair of bars carried by and disposed on opposite sides of and insulated from said switch arm and extended thereabove on opposite sides of said barrier and arranged to cooperate with said stationary switch members, and means electrically connecting said bars. 40

45 In testimony whereof, I have signed my name to this specification.

CHESTER D. AINSWORTH.
